UNITED STATES PATENT OFFICE.

MANFRED ARON, OF CHARLOTTENBURG, NEAR BERLIN, AND WILHELM KEPPEL, OF BERLIN, GERMANY, ASSIGNEES TO THE FIRM OF PROGRESS, MOTOREN- UND APPARATENBAU G. M. B. H., OF CHARLOTTENBURG, NEAR BERLIN, GERMANY.

ELECTRIC INCANDESCENT LAMP.

1,260,742.

Specification of Letters Patent. Patented Mar. 26, 1918.

Application filed December 19, 1913. Serial No. 807,705.

To all whom it may concern:

Be it known that we, MANFRED ARON, managing director, residing at Charlottenburg, near Berlin, Germany, and WILHELM KEPPEL, engineer, residing at Berlin, Germany, both citizens of Germany, subjects of the King of Prussia and Emperor of Germany, have invented new and useful Improvements in and Relating to Electric Incandescent Lamps, of which the following is a specification.

This invention relates to electric incandescent lamps of the kind in which the luminous filaments or glowers or portions thereof are arranged in a definite shape or form for advertising or other purposes.

The invention relates more particularly to incandescent lamps of which the filaments or glowers represent letters, numbers, signs, words or pictures of any desired description and has for its object to overcome certain difficulties hitherto experienced in the construction and use of such lamps.

A difficulty in connection with lamps of this character is the reflection of light from the surfaces of the lamp which, while not objectionable in lamps employed for ordinary illumination, causes a want of distinctness and clearness in the case of lamps of the kind to which the invention relates.

According to the present invention the improved lamps are so constructed that objectionable reflections from portions of the lamp bulb are obviated.

The invention is illustrated in the accompanying drawings of which Figures 1 and 2 are views in side elevation of incandescent lamps constructed in accordance with the invention, Fig. 3 being a similar view but illustrating a number of lamps connected in circuit with one another together with compensating resistances which will be herein-after described.

Fig. 4 is a transverse sectional view of one of the lamps shown in Fig. 3.

In order to enable the lamps to be connected in circuit with one another and interchanged, each of the lamp filaments is arranged to have the same electrical resist-

ance, any variation in the length of the filaments being compensated for by an additional resistance forming a part of the internal circuit of each lamp. This additional resistance may be constituted by resistance wires or members and may be of any desired form or construction. In the arrangement shown in Fig. 1 the additional resistance is located within the lamp bulb itself the filament of the lamp, which is of definite length and form being indicated at *a* and the additional resistance indicated at *c* being located within the interior of a hollow container composed for instance of glass indicated at *b*.

In the modified arrangement illustrated in Fig. 2 the additional resistance is located as indicated at *c* in the portion of the bulb adjacent to the cap of the lamp. In the construction illustrated in this figure the additional resistance is invisible, the upper part of the lamp bulb indicated at *z* being frosted or obscured. The same effect can evidently be obtained by locating the compensating resistance at any suitable point within the lamp bulb and arranging a non-transparent screen in front of the resistance or an external screen may be provided covering the resistances of a group of lamps constituting an illuminated sign. In these cases the resistances may be of such nature or arranged under such conditions, that they are glowing when the lamps are at work.

In a particularly simple construction of the lamp the filament or glower is made of greater length than is actually required by the form of the letter, sign or number to be represented, the portions of the filament not required to be visible being shielded or screened in any suitable manner. An arrangement of this kind is illustrated in Fig. 3 of the drawings, the left hand lamp of which represents the letter J, the portion *i* of the lamp filament *a* being covered or surrounded by an opaque casing or screen *k* so that this portion of the filament is invisible to the observer; this portion of the filament may be used for throwing light in another direction. It will be readily understood that in this manner lamps represent-

ing different letters or numbers may be constructed having filaments of equal length so that the resistance of each lamp is the same and they can consequently be interchanged 5 or connected together without difficulty.

From the above description it will be understood that a number of lamps, each representing a different letter, number or the like, may be connected together in series so 10 as to represent words or combinations of numbers and in such cases the number of lamps required in a single series group may be insufficient for the supply circuit voltage. In order to remedy this defect additional resistances are provided each corresponding to the resistance of one or more of the individual lamps these resistances being provided with lamp caps and sockets in the ordinary form so that one or more of 15 these resistances can be connected in a series group containing the lamps representing the letters or signs required. The additional resistances may be in the form of lamps the whole of the filament of which is invisible 20 to the observer or may be constituted by non-luminous resistances.

A series group of the kind above described is illustrated in Fig. 3 of the drawings in which two lamps representing the letters J 30 A are connected in series with two additional resistances necessary to complete the total resistance of the circuit necessary for the voltage supply available. It will thus be seen that the two additional resistances 35 shown on the right hand side of the figure replace two lamps which will be utilized in the event of a word of four letters having to be represented. In the case of one of these additional resistances the resistance body c 40 is arranged in a suitable lamp bulb or container e and is provided with a lamp cap d of the usual type. The other additional resistance at the extreme right hand of the drawing comprises a lamp bulb of the usual 45 form inclosing the resistance wire e which is inclosed in an opaque casing indicated at b.

In order to insure that the letter or figure 50 or the like represented by the filament or glower shall always directly face the observer, the central contact of the lamp cap or the contact plate of the lamp holder is arranged to be resilient so that an effective electrical connection is made before the 55 lamp bulb is completely screwed into position in the holder. The lamp can therefore be rotated through a considerable range without being disconnected from the supply circuit and its position can be adjusted 60 so that the filament or glower occupies the desired plane.

In case of the lamp representing the letter J in Fig. 3, the central contact of the lamp cap d is provided with a spring projection h

forming a resilient contact member. The 65 portions of the lamp filament forming the letter in question are mounted upon a suitably formed glass stem or carrier f to which the filament is attached by means of supporting wires g. The compensating resist- 70 ances or non-luminous part of the filament is located in an opaque casing b forming a portion of the stem or carrier f.

In the case of the other lamp representing the letter A, the compensating resistance indicated at c is located within the cap of the lamp and the internal contact of the lamp holder h is in this case provided with a resilient extension or projection.

In order to prevent objectionable reflections from the lamp bulb the portions of the latter which are so situated as to cause such reflection, are according to the present invention constructed of ground glass, for instance the portion of the wall of the bulb 85 behind and on each side of the filament or glower, the stem or carrier for the filament and the cover or casing of the resistance are obscured in this way by utilizing any suitable method for the purpose, such for instance as treatment with corrosive material, a sand blast or other suitable means.

As will be readily understood, it is particularly necessary to treat the inner portions of the glass bulb and the carrier of the 95 filament or glower in this manner and the corresponding outer surface of this portion of the bulb can if desired also be frosted, ground or constructed of dark colored glass having a mat surface. The effect of the 100 luminous filaments is also enhanced if in addition to frosting or coating the internal surface of the lamp bulb behind the filament, the corresponding external surface of the bulb is provided with a dark coating by 105 the application for instance of black varnish, in which case the portion of the lamp bulb behind the filament appears to have a dark mat surface so that the luminous filament stands out clearly from this background and presents the letter, number or 110 the like in a particularly effective manner.

The glass stem or carrier may evidently be similarly treated for obtaining the same 115 purpose.

In Figs. 3 and 4 of the drawings the portions of the lamp thus treated are indicated in hatched lines and as will be seen from Fig. 4, the rear half of the lamp bulb is thus treated as well as the stem or carrier f.

The invention is evidently not limited to the precise construction and details above described which can be modified to meet particular conditions.

Having now described our invention what 125 we claim and desire to secure by Letters Patent of the United States is:

1. An electric incandescent lamp, in which

the carriers for the filament are rendered non-reflecting.

2. An electric incandescent lamp, in which the internal surface of the bulb behind the 5 filament is rendered non-reflecting, and the corresponding external surface of the bulb is rendered dark mat.

In testimony whereof we have hereunto

set our hands in presence of two subscribing witnesses.

MANFRED ARON.
WILHELM KEPPEL.
